UNITED STATES PATENT OFFICE.

JEROME R. GRAVES, OF CORRY, PENNSYLVANIA, ASSIGNOR OF ONE-HALF HIS RIGHT TO JAMES GUY FOREMAN, OF SAME PLACE.

IMPROVEMENT IN WATCH-JEWEL ASSORTERS.

Specification forming part of Letters Patent No. 173,782, dated February 22, 1876; application filed January 29, 1876.

To all whom it may concern:

Be it known that I, JEROME R. GRAVES, of Corry, in the county of Erie and State of Pennsylvania, have invented certain new and useful Improvements in Watch-Jewel Assorter; and I do hereby declare the following to be a full, clear, and exact description of the invention, such as will enable others skilled in the art to which it pertains to make and use it, reference being had to the accompanying drawings, which form part of this specification.

My invention relates to an improvement in watch-jewel assorters; and it consists in a number of cups placed one above the other, each one of which has a perforated bottom, the holes of which are slightly larger than those in the cup below, so that when the jewels are poured into the top cup and then shaken they will fall from one cup to another until each size is assorted to its proper number, as will be more fully described herein-after.

The accompanying drawings represent my invention.

a represent a number of cups, each one of which has a perforated concave bottom, *c*, and is made to fit on the top of the one just below in such a manner that they cannot be easily displaced sidewise. The holes in each bottom

are just one size larger than the ones in the bottom beneath, so that when jewels of different sizes are poured into the top cup, and then the cups are shaken sidewise, the jewels fall from one cup to another until they are all assorted, each size by itself.

Watch-jewels are sold by the gross, in assorted sizes, and when the watchmaker wants one of a particular size he must look over the whole gross to get it, and thus much time is lost. By means of my invention they can all be assorted in a few minutes, and then, by putting them in small bottles and numbering each bottle with the number or size of the cup, he can always at once select the size he wants.

Having thus described my invention, I claim—

A jewel-assorter, consisting of a number of cups, *a*, having perforated bottoms *c*, the holes in each bottom being one size larger than the one just below it, substantially as shown and described.

In testimony that I claim the foregoing I have hereunto set my hand this 11th day of January, 1876.

JEROME RUSSELL GRAVES.
